UNITED STATES PATENT OFFICE.

CHARLES HABERMAN, OF NORTH BERGEN, NEW JERSEY, ASSIGNOR TO OSCAR SCHMIDT, INC., OF JERSEY CITY, NEW JERSEY, A CORPORATION OF NEW JERSEY.

PLAYING DEVICE FOR STRINGED MUSICAL INSTRUMENTS.

1,346,707.

Specification of Letters Patent.

Patented July 13, 1920.

Application filed August 21, 1919. Serial No. 318,920.

To all whom it may concern:

Be it known that I, CHARLES HABERMAN, a citizen of the United States, and a resident of North Bergen, in the county of Hudson and State of New Jersey, have invented a new and Improved Playing Device for Stringed Musical Instruments, of which the following is a full, clear, and exact description.

10 The invention relates to stringed musical instruments of the zither type, and its object is to provide a new and improved playing device more especially designed for playing the melody strings without the use of picks. Another object is to construct the playing device in a very simple and effective manner and with a view to prevent the parts from getting out of order. Another object is to enable the player to sound the strings 15 with a tremolo effect in case such is desired or called for by the music.

With these and other objects in view, the invention consists of certain novel features of construction, as hereinafter shown and 20 described and then specifically pointed out in the claims.

A practical embodiment of the invention is represented in the accompanying drawings forming a part of this specification, in 25 which similar characters of reference indicate corresponding parts in all the views.

Figure 1 is a plan view of the playing device applied to the melody strings of a zither;

30 Fig. 2 is an enlarged cross section of the same on the line 2—2 of Fig. 1;

Fig. 3 is a sectional plan view of the same on the line 3—3 of Fig. 2; and

Fig. 4 is a cross section of one of the 35 strikers, the section being on the line 4—4 of Fig. 3.

The body 10 of the musical instrument is of box-like construction, and over the said body are stretched in the usual manner 40 melody strings 11 arranged in pairs, and accompaniment strings 12. The improved playing device is shown applied to the melody strings 11 for sounding the same as hereinafter more fully explained, and the 45 said playing device is mounted on a support 15 extending across the melody strings 11 and having legs 16 at its ends resting on top of the body 10 and secured thereto by screws 17 or other fastening means.

The melody strings 11 are adapted to be 55 sounded by strikers 20, one for each pair of melody strings, each being made of a flexible member 21 of flat steel, and a pivot member 22, preferably of non-flexible material. The flexible member 21 is provided at its 60 forward end with a head 23 adapted to strike the corresponding pair of melody strings 11. The rear portion of the flexible member 21 overlies the front portion of the member 22, and the forward end of the member 22 is provided with integral clamping lugs 26 bent over onto the flexible member 21 to securely fasten the latter in position on the pivot member 22. The pivot member 22 is provided with a struck-up 65 half round bearing 24 seated on a pivot rod 25 secured at its ends in the legs 16 of the support 15. By the arrangement described, the pivot member 22 can be readily placed in position on the top of the pivot rod 25 and is free to swing thereon. In practice, 70 the pivot member 22 is considerably wider than the flexible member 21, and the side edges of the adjacent pivot members 22 are in abutting relation to hold the strikers at 75 all times in proper striking relation relative to the melody strings 11. The pivot member 22 is provided in the rear of the bearing 24 with an integral seat 30 in which is seated the lower end of a spring 31 fitting 80 with its upper end into a seat 32 formed in the under side of the support 15. By the arrangement described, the striker is normally held in an uppermost position by the spring 31, that is, with the head 23 a distance 85 above the corresponding pair of melody strings 11. The rear end of the pivot member 22 of each striker 20 is provided at its under side with a block 35 of felt or other suitable material and normally 90 engaging the corresponding pair of melody strings 11 to damp the same.

In order to actuate the strikers individually, use is made of keys 40 mounted to slide vertically in the support 15. Each of the keys 40 comprises a stem 41 mounted to slide up and down in a bearing 42 formed in the support 15, and the lower end of the stem 41 is provided with a collar 43 seated on top of the rear portion of the flexible member 21 of the corresponding striker 20. The upper end of the shank 41 is provided with a finger piece 45, the bottom of which 100

105

is normally a distance above the top of the support 15, as plainly shown in Fig. 2, but when the finger piece 41 is depressed by the player then a downward swinging movement is given to the corresponding key 20 whereby the head 23 of the striker is moved into striking engagement with the corresponding pair of melody strings 11 to sound the same. The downward movement of the 10 key 40 is limited by the bottom of the finger piece 45 striking against the top of the support 15. It is understood that when the striker 20 is swung downward on pressing its key 40 then the spring 31 is compressed 15 and when the operator releases the finger piece 45 the key 20 returns to its normal uppermost position by the action of the spring 31. By providing the flexible member 21, it is evident that a rebounding action is had after the head 23 strikes the 20 corresponding pair of melody strings 11, and when the finger piece 45 is held pressed the head 23 repeatedly strikes the string thereby producing a tremolo effect. When 25 a striker 20 is swung downward on depressing its key 40 as above explained then the damping block 35 is lifted off the corresponding pair of strings 11 to allow proper sounding thereof by the head 23 of the 30 striker, and when the latter returns to uppermost position after releasing the finger piece 45 then the damping block 35 again engages the corresponding pair of melody strings 11 to damp the same. When the 35 finger piece 45, however, is quickly released by the player then the string is sounded but once by the striker. By seating the key 40 on the rear portion of the flexible member 21 of steel the wear is reduced to a minimum 40 and consequently long life of the playing device is insured.

It will be noticed that by constructing the striker in the manner described it can be cheaply manufactured and the several 45 strikers can be quickly assembled without requiring skilled labor.

Having thus described my invention, I claim as new and desire to secure by Letters Patent:—

- 50 1. The combination with a stringed musical instrument of a support extending across a series of strings, a pivot rod held on the said support above the said strings, and strikers mounted to swing on the said rod and arranged in striking relation to the said strings, each striker having a flexible member and a pivot member on which the flexible member is secured, the pivot member having a struck up half round bearing 55 seated on the pivot rod, the pivot members of the several strikers being wider than the flexible members and having abutting side edges to hold the strikers in striking relation with their strings.

2. The combination with a stringed musical instrument of a support extending across a series of strings, a pivot rod held on the said support above the said strings, and strikers mounted to swing on the said rod and arranged in striking relation to the 65 said strings, each striker having a flexible member and a pivot member on which the flexible member is secured, the pivot member having a struck up half round integral bearing seated on the pivot rod, the said pivot member having a seat on top in the rear of the said pivot rod and the under side of the said support having a seat in alignment with the said striker seat and a spring seated in the said seats. 75

3. The combination with a stringed musical instrument of a support extending across a series of strings, a pivot rod held on the said support above the said strings and strikers mounted to swing on the said 80 rod and arranged in striking relation to the said strings, each striker having a flexible member, a pivot member on which the flexible member is secured, the pivot member having a struck up, half round bearing 85 seated on the pivot rod, and damping blocks attached to the under side of the said pivot members at the rear ends thereof to dampen the corresponding strings on the return movement of the strikers after having 90 sounded their strings.

4. In a playing device for stringed musical instruments, a striker comprising a flexible striking member provided at its outer end with a striking head, and a pivot 10 member of flat rigid material and to which the rear end of the said flexible member is secured, the said pivot member having a struck up half round pivot bearing intermediate its ends, the said pivot member being 1 wider than the said flexible striking member, the forward end of said pivot member being provided with clamping lugs bent over the said striking member to fasten the latter in position on the pivot member. 1

5. In a playing device for stringed musical instruments, a striker comprising a flexible striking member provided at its outer end with a striking head, a pivot member of flat rigid material and to which the 1 rear end of the said flexible member is secured, the said pivot member having a struck up, half round pivot bearing intermediate its ends, the said pivot member being wider than the said flexible striking member, the forward end of the said pivot member being provided with integral clamping lugs bent over the said striking member to fasten the latter in position on the pivot member, and a spring seat formed in the pivot member in the rear of the said bearing. 1

CHARLES HABERMAN.
